CLAIM

The ornamental design for a butt pad for a rifle stock, as shown and described.

DESCRIPTION

FIG. 1 is a left/top/rear perspective view of the butt pad for a rifle stock.

FIG. 2 is a left plan view of the butt pad for a rifle stock.

FIG. 3 is a right plan view of the butt pad for a rifle stock.

FIG. 4 is a front plan view of the butt pad for a rifle stock.

FIG. 5 is a rear plan view of the butt pad for a rifle stock.

FIG. 6 is a top plan view of the butt pad for a rifle stock.

FIG. 7 is a bottom plan view of the butt pad for a rifle stock.

FIG. 8 is a right/top/front perspective view of the butt pad for a rifle stock.

FIG. 9 is a left/bottom/front perspective view of the butt pad for a rifle stock.

FIG. 10 is a right/bottom/front perspective view of the butt pad for a rifle stock; and,

FIG. 11 is a left/top/front perspective view of the butt pad for a rifle stock.

The broken lines showing of the depth of the recesses on the sides of the butt pad for a rifle stock are included for the purpose of illustrating environment and forms no part of the claimed design.
